* cited by examiner

Primary Examiner—Holly H Bayham*Assistant Examiner*—Cynthia M Chin(74) *Attorney, Agent, or Firm*—John A. Doninger(57) **CLAIM**

The ornamental design for a handle for kitchen implements, as shown and described.

DESCRIPTION

FIG. 1 is a top, left side and rear perspective view of the handle for kitchen implements showing our new design;

FIG. 2 is a left side elevation view, the right side being a mirror image thereof;

FIG. 3 is a rear elevation view thereof;

FIG. 4 is a front elevation view thereof;

FIG. 5 is a top plan view thereof;

FIG. 6 is a bottom plan view thereof; and,

FIG. 7 is a bottom, left side and rear perspective thereof.

The broken line showing environmental structure is for illustrative purposes only and forms no part of the claimed design.
